DESIGN FOR A TEXTILE FABRIC

Philip Leslie Cherry, Philadelphia, Pa., assignor to E. L. Mansure Co., Chicago, Ill., a corporation of Illinois

Application December 9, 1936, Serial No. 66,403

Term of patent 7 years

To all whom it may concern:

Be it known that I, Philip Leslie Cherry, a subject of the King of Great Britain, residing at Philadelphia, in the county of Philadelphia and Commonwealth of Pennsylvania, have invented a new, original, and ornamental Design for a Textile Fabric, of which the following is a specification, reference being had to the accompanying drawing, forming a part thereof.

I claim:

The ornamental design for a textile fabric, as shown and described.

PHILIP LESLIE CHERRY.
